UNITED STATES PATENT OFFICE.

WILLIAM SCHAAKE, OF PITTSBURGH, PENNSYLVANIA, ASSIGNOR TO WESTINGHOUSE ELECTRIC & MANUFACTURING COMPANY, A CORPORATION OF PENNSYLVANIA.

TRACKLESS TROLLEY.

Application filed November 9, 1921. Serial No. 513,869.

To all whom it may concern:

Be it known that I, WILLIAM SCHAAKE, a citizen of the United States, and a resident of Pittsburgh, in the county of Allegheny and State of Pennsylvania, have invented a new and useful Improvement in Trackless Trolleys, of which the following is a specification.

My invention relates to current collectors 10 and, particularly, to means for mounting a plurality of contact devices upon a single supporting member.

My invention is designed especially for employment in connection with trolley busses or trackless trolleys wherein contact members or current collectors are employed to co-operate with a pair of trolley wires. When such collectors are mounted upon a single pole, provision must be made to permit 20 the vehicle to turn from its normal path of movement, while, at the same time, retaining the current collectors in engagement with their respective trolley wires.

The object of my invention is to provide 25 an improved and simplified form of multiple-contact structure whereby engagement between the contact members and the trolley wires will be efficiently maintained, notwithstanding deviations in the path traveled by 30 the vehicle upon which the contact members are mounted.

In the accompanying drawings, Figure 1 is a view of my trolley pole in front elevation,

35 Fig. 2 is a view thereof in side elevation, and

Fig. 3 is a diagrammatic illustration of the positions assumed by various portions of the mechanism under certain conditions 40 of operation.

I provide a pole 4 that may be mounted upon the roof of a vehicle (not shown) upon a swivel base and normally biased upwardly in the usual manner.

45 The pole carries, at its upper end, a pair of arms 5 and 6 that are pivoted at 7 and 8, respectively, for movement in a direction transversely of the pole 4.

The arms 5 and 6 carry, at their upper 50 ends, swivels 9 and 10, respectively, in which are supported trolley wheels 11 and 12 that co-operate with a pair of trolley wires 13 and 14. The arms 5 and 6 are guided and maintained in properly spaced relation to 55 the longitudinal center line of the pole 4

by means of equalizing link members 16 that are connected to lugs 17 of the arms 5 and 6. The other ends of the links 16 are pivotally connected to a yoke member 18 that embraces the pole 4 and has sliding engagement therewith. The yoke 18 is engaged, at its opposite sides, by springs 19 and 20 that encircle the pole 4 and abut fixed collars 22 and 23 respectively. The springs 19 and 20 tend to yieldingly maintain the yoke 18 at a point midway between the collars 22 and 23, but if, during the operation of the vehicle, a place in the line were reached where the wires 13 and 14 were in abnormal spaced relation with respect to one another, the arms 5 and 6 could move toward or away from each other, as might be required to adjust themselves to the spacing of the wires, moving against either the tension of the spring 20, in case 70 the wires were abnormally near each other, or against the compression of the spring 19, in case the wires were spaced further apart than normal.

It will be observed that, by reason of the 80 link connection, the arms 5 and 6 will each move half the distance required to accommodate the positions of the current collectors to those of their associated trolley wires.

The arms 5 and 6 are each made in two spaced sections that are joined by insulating connections 24, and flexible current conductors 25 are connected to the upper ends of the arms 5 and 6 and thence lead down, 90 through the trolley pole 4, to the apparatus within the trolley car.

If the arms 5 and 6 were movable independently, it would sometimes happen that the required movement to accommodate the 95 current collectors to the lateral spacing of the wires would be made by one arm alone, in which case the trolley pole and its current collectors would be thrown out of balance and consequent liability of displacement of the current collectors.

In order to prevent entanglement of the apparatus with the wires 13 and 14, and consequent short circuits, should the wheels leave the wires, I provide a bar 27 of insulating material that is loosely supported, by chains 28 and 29, from the upper ends of the arms 5 and 6.

Fig. 3 shows the positions occupied by the trolley pole and the current collectors 110

- with respect to the trolley wires when the bus has passed from its normal position beneath the wires. It will be observed that the swivel harps permit the wheels to maintain their parallelism with the trolley wires. In this case also, it will be observed that, though the spacing between the wires 13 and 14 is normal, the distance between the trolley wheels 11 and 12 is increased, by reason of the diagonal position of the trolley pole with respect to the trolley wires, and here, again, the advantage of having the current collectors mounted upon the pivoted arms 5 and 6 is apparent.
15. What I claim as my invention is:
1. The combination with a trolley pole, of a pair of arms, each mounted at one end to the pole for movement transversely thereof and at its opposite end provided with a current collector, a barrier disposed between the arms, and flexible connections between the barrier and the arms.
  2. The combination with a trolley pole, of a pair of arms, each mounted at one end to the pole for movement transversely thereof and at its opposite end provided with a current collector, a barrier disposed between the arms, and an extensible connection between the barrier and one of the arms.
  3. The combination with a trolley pole, of a pair of arms, each mounted at one end to the pole for movement transversely thereof and at its opposite end provided with a current collector, a barrier disposed between the arms, connections between the barrier and the arms, and means for permitting the arms to move relatively to each other.
  4. The combination with a trolley pole, of a pair of arms, each mounted at one end to the pole for movement transversely thereof and at its opposite end provided with a current collector, a barrier disposed between the arms, connections between the barrier and the arms, and means for permitting the arms to move relatively to each other in a direction transversely of the pole.
  5. The combination with a pair of independently movable current collector supports and a collector carried by each, of a barrier disposed therebetween adjacent to the collectors and having flexible connections with the supports.
6. The combination with a pair of independently movable current collector supports and a collector carried by each, of a barrier disposed therebetween adjacent to the collectors and having an extensible connection with one of the said supports.
7. The combination with a trolley pole, of a pair of upwardly extending contact-carrying arms supported thereby, and a barrier disposed between the upper ends of the arms.
8. The combination with a trolley pole, of a pair of upwardly extending contact-carrying arms supported thereby, and a barrier loosely supported between the upper ends of the arms.
9. The combination with a trolley pole, of a pair of upwardly extending contact-carrying arms pivotally supported by the pole and a barrier connected to the upper ends of the said arms.
10. The combination with a trolley pole, of a pair of upwardly extending contact-carrying arms pivotally supported by the pole, a barrier disposed between the upper ends of the arms, and a loose connection between the barrier and one of the said arms.
11. The combination with a trolley pole, of a pair of upwardly extending contact-carrying arms pivotally supported by the pole, a barrier supported by the arms, and a connection for permitting those portions of the respective arms adjacent to the barrier to move relatively to each other.
12. The combination with a trolley pole, of a pair of upwardly extending contact-carrying arms supported thereby, and a semi-rigid barrier disposed between the upper ends of the arms.
13. The combination with a trolley pole, of a pair of upwardly extending contact-carrying arms supported thereby, and a barrier loosely supported between the upper ends of the arms.

In testimony whereof, I have hereunto subscribed my name this 2nd day of November, 1921.

WILLIAM SCHAAKE.
